GAME APPARATUS

James Julian Carr, Richmond, Va.

Application November 27, 1935, Serial No. 51,898

12 Claims. (Cl. 273—95)

The invention relates to a game apparatus and more particularly to a ball throwing and catching machine.

The primary object of the invention is the provision of an apparatus of this character, wherein mechanically a series of balls will be thrown and when in motion a person endeavors to catch the same and on each successful catching of a ball a score is had, the person catching the ball is required to use skill for a successful catch and at the same time such person needs to be very active so that the muscles of the body will be exercised and in this manner promoting health through the use of the apparatus.

Another object of the invention is the provision of an apparatus of this character, wherein the balls when thrown will be deflected from a straight course and thus an operative is required to be alert for successful catching of the balls for high scoring and quick judgment being necessary in view of the irregularity in the throw of the balls for the successful catching of the same, the apparatus when in use assures to an operative considerable fascination and amusement and exercise with a high degree of skill.

A further object of the invention is the provision of an apparatus of this character, wherein the balls will be automatically brought into position for the throwing thereof, this being had mechanically and likewise the catching of the ball is mechanically effected, the apparatus being controlled electrically and by the deposit of a coin in a coin medium, the balls being automatically handled so that it is unnecessary for an operative to manually handle such balls either for the throwing or the catching thereof.

A further object of the invention is the provision of an apparatus of this character, wherein an adjustment is provided whereby the operative can regulate the amount of force required to actuate the catching device.

A further object of the invention is the provision of an apparatus of this character, wherein the construction thereof is novel in its entirety, affording entertainment and exercise for an operative as well as skill for scoring purposes.

A still further object of the invention is the provision of an apparatus of this character, which is comparatively simple in its construction, electro-mechanically operated, thoroughly reliable and efficient in its operation, attractive and fascinating, serviceable for exercising purposes, and inexpensive to manufacture and install.

With these and other objects in view, the invention consists in the features of construction,

combination and arrangement of parts as will be hereinafter more fully described, illustrated in the accompanying drawings, which disclose the preferred embodiment of the invention and pointed out in the claims hereunto appended.

In the accompanying drawings:

Figure 1 is a fragmentary vertical sectional view through an enclosure showing the apparatus constructed in accordance with the invention associated therewith and illustrating an operative playing the apparatus.

Figure 2 is a horizontal sectional view thereof.

Figure 3 is an enlarged fragmentary vertical sectional view through the ball throwing mechanism and adjuncts.

Figure 4 is a fragmentary sectional view on the line 4—4 of Figure 2.

Figure 5 is a fragmentary side elevation of the ratchet mechanism shown in Figure 6.

Figure 6 is a top plan view of the mechanism shown in Figure 5.

Figure 7 is a diagrammatic elevation showing the steps of control of the electric magnet switch controlled by the mechanism shown in Figures 5 and 6.

Figure 8 is a fragmentary sectional view showing in detail the ball elevator or lifter mechanism of the apparatus.

Figure 9 is a horizontal sectional view thereof.

Figure 10 is an enlarged vertical sectional view showing the manner of holding the ball to be thrown by the apparatus.

Figure 11 is a sectional view on the line 11—11 of Figure 3 looking in the direction of the arrows.

Figure 12 is a sectional view on the line 12—12 of Figure 3 looking in the direction of the arrows.

Figure 13 is an enlarged elevation of the catching mechanism of the apparatus.

Figure 14 is a sectional view on the line 14—14 of Figure 13 looking in the direction of the arrows.

Figure 15 is a sectional view on the line 15—15 of Figure 13 looking in the direction of the arrows.

Figure 16 is an elevation of the scoring device.

Figure 17 is a diagrammatic plan view showing the electric circuit system or arrangement of the apparatus and looking from the rear side thereof.

Similar reference characters indicate corresponding parts throughout the several views in the drawings.

Referring to the drawings in detail, A designates generally a portion of an enclosure or room having an inclined foundation or flooring 10 and front and rear vertical walls 11 and 12, respectively. The wall 11 has fitted therewith a glass paneled swinging door 13 for entrance and exit.

to and from the enclosure or room A, this door being automatically closed in any suitable manner.

Outside of the enclosure or room A is located next to the wall 12 ball throwing mechanism involving a vertical stand 14 in which is arranged a horizontal slideable plunger 15 having the head 16 working within a barrel 17 carried by said stand. Within this barrel 17 and playing against the head 16 is a coiled expansion spring 18 which urges the plunger 15 in a direction for ball throwing.

Within the stand 14 beneath the plunger 15 is a rotatable cam disk or wheel 19 which functions as a resetting and release element for the plunger 15, it having the diametrically opposed receded and projected cam areas 20 and 21, respectively, for coaction with a trigger 22 on the plunger 15. The areas 20 are adapted in cooperating with the trigger 22 to free the same for the projecting of the plunger 15 under the action of the spring 18 while the areas 21 retract the plunger in cooperation with the trigger 22 against the resistance of the spring 18 and thus hold the plunger 23 cocked for a determined period. The arbor 23 which is journaled in the stand 14 has fixed thereto a gear 24, it meshing with a pinion 25 fast upon the power shaft 26 of an electric motor 27 carried upon a shelf 28 on the stand 14. This motor is arranged in an electric circuit 29 tapped in with an electric feed line 30 and such circuit 29 extends to a coin box 31 conveniently placed within the enclosure or room A and within this box and included in said circuit 29 is a coin controlled switch 32 which on the deposit of a determined coin within the box 31 will close said circuit 29 for the starting of the motor 27.

Built onto the wall 12 of the enclosure or room A is a casing 33 which has a wall 34 confronting the plunger 15 and this wall has provided therein a ball seat 35 combined with an opening 36 in the path of the plunger 15 so that when the plunger is moved under the action of the spring 18 the ball 37 in the seat 35 will be struck thereby for the throwing of such ball. Within the casing 33 is a funnel shaped guide mouth piece 38, the wider open end thereof being next to the ball seat 35 and this end is pivotally hung at 39 in a hanger yoke 40, it having a center stem 41 swiveled in a bearing 42 mounted exteriorly on the casing 33. The mouth piece 38 forwardly of the hanger yoke 40 rests upon cams 43, their axles 44 being suitably journaled and carry worm gears 45 meshing with worm screws 46 on a drive shaft 47 suitably journaled in the said casing 33 crosswise thereof and this shaft is driven through chain and sprocket connections 48 with the motor 27. The cams 43 when active effect a jiggling momentum to the mouth piece 38 and thus on the passing of the ball 37 through the latter it will be given a diversified course within the enclosure or room A. The mouth piece 38 is maintained in contact with the cams 43 by tensioning springs 49 working against the said mouth piece from above the same and within the said casing 33.

At one side of the casing 33 is a vertical housing 50 in which is disposed a ball lift or elevator in the form of an endless belt 51 traveling over guide rollers 52 and operated by friction rollers 53, these through chain and sprocket connections 54 are driven by the motor 27 so that a positive drive is assured. The belt 51 has thereon the ball steps or rests 55 for balls 37 singly delivered to the lift from a return chute or tube 56 built beneath the foundation or flooring 10 of the

enclosure or room A and inclined toward the said lift or elevator as well as from the top surface of the floor or foundation 10 through a hole 57 leading to said chute or tube 56. Partly about the hole 57 between it and the wall 12 is a shield or guard 58 for directing the balls 37 therein when rolling upon the foundation or floor 10 following the inclination thereof.

The seat 35 in the wall 34 of the casing 33 for the balls 37 has confronting the same spring tensioned retaining jaws 59 for maintaining the seating of a ball in position to be struck or thrown by the action of the plunger 15 and this seat is in communication with a feed trough 60 leading from the housing 50 and inclined in the direction of said seat so that balls upon the steps or rests 55 of the belt 51 will gravitate to the seat 35 from the elevator or lift and when a step or rest 55 reaches the trough 60 the ball 37 thereon will be acted upon by a kick spring 61 within the housing 50 and thus cause the kicking of the balls into the trough 60 for the feed of such balls singly into a position to be thrown by the plunger successively.

Located the required distance from an opening 62 in the wall 12 for the admission of the ball 37 into the enclosure or room A when thrown by the plunger 15 is a ball catching throat piece 63 fitting a flexible hose 64 extending from a coupling 65 joining it with the chute or tube 56. The throat piece 63 is carried by clips 66 on a handle bar 67, it having the laterally extended hand grips 68 at opposite sides thereof. The handle bar through extension ears 69 has loose connection with pivots 70 fitting the lower eye ends 71 of suspension rods 72, these being pivoted at 73 to a cross head 74 forming a carrier. The cross head 74 is slidably fitted on vertically disposed guide rods 75 rigidly secured in and hung from a ceiling plate 76, the lower ends of the guide rods 75 being connected with angular braces 77 which are also fixed to the ceiling 78 of the enclosure or room A. Surrounding the guide rods 75 are coiled springs 79 which are made fast to the ceiling plate 76 and to the cross head 74 and the tension of these springs is such as to normally maintain the cross head at a point midway of the extent of the guide rods 75 and thus allowing this cross head to be moved upwardly or downwardly against the resistance of the said springs 79 by sliding on the guide rods 75 under manual manipulation of the throat piece 63. The suspension rods 72 are disposed in parallel relation to each other and their pivotal connection with the handle bar 67 and the cross head 74 permits of the swinging laterally of the throat piece 63 while the cross head 74 can slide perpendicularly on the guide rods 75. The handle bar 67 at the hand grips 68 thereof is adapted to be manually manipulated by an operative so that the throat piece 63 can be positioned in the path of the thrown ball for the catching of such ball therein.

On the ear extension 69 of the handle bar 67 is a rack 80 carrying a face shield 81 for the operative to prevent a thrown ball striking the face of the operative when manipulating the throat piece 63 by hand.

Arranged in the enclosure or room A above the opening 62 on the wall 12 to be clearly visible to the operative is a registering device including a box 82 having therein a dial face 83 exposed through the transparent or open front of said box and this dial carries digits or numerals 84 ranging from zero to nineteen, the same being 75

disposed concentrically to the arbor 85 for a movable pointer or hand 86 which traverses the dial 83 for registering the balls caught in the throat piece 63 by manipulation by the operative. 5 The arbor 85 has fixed thereto a coiled clock spring 87 which is also fixed within the box 82 and this arbor 85 has fixed thereto a counting wheel 88 and its teeth 89 have coacting therewith a ratchet dog 90 controlled by an electric magnet 91 included in an electric circuit 92. The dog 90 tends to oppose the spring 87 which turns the counting wheel 88 in one direction. The dog 90 is released from the wheel 88 by the magnet 91 when energized. Coacting with the counting 10 wheel 88 is an actuator lever 93, it being pivoted at 94 and is controlled by an electric magnet 95 arranged in a circuit 96 which includes a switch 97 having a closing arm 98 extended into the coupling 65 and this switch 97 is normally opened 15 and is automatically closed when a ball 37 passes through the coupling 65 and actuates the closing arm 98 of said switch. In doing this the lever 93 moves the counting wheel 88 a single tooth causing the pointer or hand 86 to be moved a single 20 digit scoring the catching of the ball in the throat piece 63. The lever 93 carries at its operating end with relation to the wheel 88 a spring tensioned tongue 99 which permits the disengagement of the said lever 93 from the teeth 89 of the wheel 25 88 when the same is turned counter-clockwise under the tension of the spring 87 on the release of the dog 90 from the said teeth 89 of the wheel, this release being had when the magnet 91 is energized and in this manner the pointer or hand 30 86 returns to normal zero position after scoring the number of catches successfully had of the ball by the throat piece 63 under the control of an operative.

The wheel 88 carries a striker 100 engageable 35 with the stem 101 of a float 102 of a dash pot 103, the stem 101 being provided with a trip 104 acting upon the armature 105 of a switch 106 included in the circuit 92 so as to open said circuit when the striker engages with the stem 101 of the 40 dash pot 103. This armature cooperates with an electric magnet 107 in a circuit 108 which also has therein a switch 109 controlled by an armature 110. This armature 110 is tripped by a trip arm 111 carried by the arbor 112 for a ratchet 45 wheel 113 in the stand 14 above the plunger 15, the arbor 112 being journaled in said stand. This trip arm 111 has limited loose play on the arbor 112 by the slot 114 in the connecting portion of said arm 111 and the pin 115 on the arbor 112. 50 The arm 111 is also acted upon by a spring 116 which functions to give the said arm 111 a snapping action when coacting with the armature 110 as shown in Figure 7 of the drawings. The ratchet wheel 113 has engaged therewith a ratchet 55 dog 117 which permits the wheel to rotate in one direction but latches it against reverse movement and such wheel is turned by the trigger 22 which carries a spring tooth 118 for engaging with the teeth of said wheel so that it will be moved a 60 single tooth on the striking stroke of the plunger 15. The ratchet wheel 113 has playing against the same a drag spring 119 which functions as a 65 brake for the said wheel. The spring tooth 118 is such as to permit the plunger to pass the teeth of the wheel 113 when the plunger 15 is pushed back to non-striking position by the cam disk or wheel 19.

In the motor circuit 29 is the magnet 120 which controls the armature 110. When a coin 75 is dropped into the coin box 31 it closes the switch

32 momentarily closing the circuit 29 to the motor 27. This closing of the circuit 29 energizes the electric magnet 120 attracting the armature 110 so that the switch 109 closes completing the circuit through the said magnet 120 and 5 through the motor 27 by the circuit 108 concurrently therewith the magnet 107 is energized closing the switch 106; this completing the circuit 92 to the magnet 91 energizing the latter and releasing the dog 90 which frees the counting 10 wheel 88 and by the spring 87 the hand or pointer 86 after having been moved for counting purposes is returned to zero position which is the normal location thereof. On the return of the pointer or indicator hand 86 to zero the 15 striker 100 operates on the stem 101 of the float 102 in the dash pot 103 the trip 104 on this stem 101 plays upon the armature 105 opening the switch 106 and thus deenergizes the magnet 91 which frees the dog 90 returning the latter to 20 latching position with the counting wheel 88. When the motor 27 is active by the closing of the switch 109 the cam wheel 19 operates and thus controlling the plunger 15 for the striking operation thereof. Concurrently therewith the elevator or lift having the belt 51 collects the balls from the tube 56 lifting the same in single order to be brought into the seat 35 so that the plunger 15 under its striking action will throw the ball through the funnel 38 for the catching 30 of such balls by the throat piece 63. Those balls successfully caught by the throat piece 63 will in passing through the coupling 65 cause electrical operation of the score device 82 as before mentioned. The balls 37 caught as well as those 35 missed will be delivered to the tube 56 for entry into the elevator or lift for the purposes hereinbefore set forth. The motor circuit 29 is broken only when the strike arm 111 has completed a 40 full revolution concurrently with the ratchet wheel 113 and in this manner the number of balls that an operative is entitled to in the playing of the apparatus is regulated, the number being congruous with the number of ratchet teeth on the said wheel 113. The bobbing movement of the float 102 of the dash pot 103 causes the trip 45 104 both on the lowering of the stem 101 and the raising thereof to automatically actuate the armature 105 for the opening of the switch 106 as will be apparent in Figure 17 of the drawings. 50

The handles 121 are threaded on pivot rods 70 and this permits manual rotation thereof for the tightening or loosening of the springs 122 which encircle the rods 70 as shown in Figures 14 and 15 of the drawings and thus increase or 55 decrease pressure on the extension ears 69 and suspension rods 72, there being provided shims 123 between these rods 72 and the ears 69.

What is claimed is:

1. In an apparatus of the character described, 60 ball throwing mechanism, means manually controlled for catching said balls, coin controlled mechanism for setting the ball throwing mechanism in action, electro-mechanical scoring means cooperating with the ball catching mechanism for registering respectively balls caught thereby, mechanism for positioning balls singly in the path of a throwing element of the ball throwing mechanism, means for deflecting a ball when thrown by the ball throwing mechanism, 65 and mechanism for jiggling the last-named means.

2. In an apparatus of the character described, 70 ball throwing mechanism, means manually controlled for catching said balls, coin controlled 75

- the ball catching mechanism for vertical and lateral adjustment of the same, mechanism for the feeding of the balls from the collecting means and delivering the same to the throwing element 5 of said ball throwing mechanism, mechanism controlled by the ball throwing element of said ball throwing mechanism for limiting the number of balls thrown thereby, a shield carried by the ball catching mechanism for an operative thereof, and 10 10 a handle bar on said ball catching mechanism and having hand grips.
10. In an apparatus of the character described, ball throwing mechanism, means manually controlled for catching said balls, coin controlled 15 mechanism for setting the ball throwing mechanism in action, electro-mechanical scoring means cooperating with the ball catching mechanism for registering respectively balls caught thereby, mechanism for positioning balls singly in the path 20 of a throwing element of the ball throwing mechanism, means for deflecting a ball when thrown by the ball throwing mechanism, mechanism for jiggling the last-named means, mechanism for setting the ball throwing mechanism, means for 25 resetting the registering mechanism, means for collecting balls from the ball catching mechanism and those missed by the latter, means suspending the ball catching mechanism for vertical and lateral adjustment of the same, mechanism 30 for the feeding of the balls from the collecting means and delivering the same to the throwing element of said ball throwing mechanism, mechanism controlled by the ball throwing element of said ball throwing mechanism for limiting the 35 number of balls thrown thereby, a shield carried by the ball catching mechanism for an operative thereof, a handle bar on said ball catching mechanism and having hand grips, and means for retaining the balls singly in the path of the throwing element of the ball throwing mechanism until 40 struck by said element.
11. In an apparatus of the character described, ball throwing mechanism, means manually controlled for catching said balls, coin controlled 45 mechanism for setting the ball throwing mechanism in action, electro-mechanical scoring means cooperating with the ball catching mechanism for registering respectively balls caught thereby, mechanism for positioning balls singly in the 50 path of a throwing element of the ball throwing mechanism, means for deflecting a ball when thrown by the ball throwing mechanism, mechanism for jiggling the last-named means, mechanism for setting the ball throwing mechanism, 55 means for resetting the registering mechanism, means for collecting balls from the ball catching mechanism and those missed by the latter, means suspending the ball catching mechanism for vertical and lateral adjustment of the same, mechanism for the feeding of the balls from the collecting means and delivering the same to the throwing element of said ball throwing mechanism, mechanism controlled by the ball throwing element of said ball throwing mechanism for limiting the number of balls thrown thereby, a shield carried by the ball catching mechanism for an operative thereof, a handle bar on said ball catching mechanism and having hand grips, means for retaining the balls singly in the path of the throwing element of the ball throwing mechanism until struck by said element, means for directing the uncaught balls to the ball collecting means when thrown by the ball throwing mechanism, and means for regulating the amount of force required to operate the ball catching mechanism.

JAMES JULIAN CARR. 55
